GEORGE H. WOOLHOUSE, OF TACOMA, WASHINGTON, ASSIGNOR OF ONE-HALF TO J. I. BOWERS, OF SEATTLE, WASHINGTON

DRY KILN

Application filed June 1, 1931. Serial No. 541,238.

My invention relates to dry kilns of the type employed for drying lumber.

Various problems are met with in the kiln-drying of lumber. The air must be kept moving continuously and at a substantially constant velocity through the lumber. The volume supplied depends upon a number of factors, among them the leakage into or from the kiln through cracks and crevices and around doors, the condition of the lumber, the particular wood, and the size of the pieces. At certain times there must be supplied a greater volume of air in a given period than at other times. It is also desirable at times to supply fresh air from outside to the air within the kiln, to replace that lost through the vents or to cause movement of the air from within the kiln through the vents. Such kilns operate for considerable periods of time and it is of course desirable to cause and keep up movement of air with the least power, and hence, it is necessary to reduce to the minimum power losses through air frictional losses in the fans employed, and through changes in direction of the air's movement. It is also desirable to prevent end drift of the air, so that it will circulate rather in a straight-through circle, that is to say, in transverse planes which are substantially at right angles to the length of the kiln.

It is also essential that the direction of movement of the air be reversed from time to time, so that the lumber will dry evenly in the pile, and so that one side of the pile will not become dry more quickly or to a greater degree than the lumber at the opposite side of the pile. It is, of course, desirable to eliminate duplication of motors and fans to cause this reversal, and to employ the same fans for advancing the air in one direction as in the opposite direction.

Constant speed motors are most desirable for operations of this type where the mechanism operates continuously for considerable periods, and it is also desirable to simplify the driving and controlling means in such a kiln.

My invention is directed to the objects in-

dictated above, enabling movement of the air in one direction or in the other with a reversible fan, several such fans being distributed along the length of the kiln, and the conduits being so arranged as to substantially eliminate end drift of the air and to keep it moving always in the given direction in a substantially plane circular path, the fan operating at constant speed and the volume being controlled, and controlled as regards the relation of one fan to the other, by simple means, and fresh air being supplied as necessary.

The principles of my invention will be best understood by reference to the accompanying drawings, wherein my invention is shown in a form which at present is preferred by me, the same embodying the principles of my invention, and in which Figure 1 is a transverse section through a kiln with lumber therein in process of drying, Figure 2 is a longitudinal section through the same, substantially on the axis of the fans, and Figure 3 is a horizontal section substantially along the line 3-3 of Figure 2.

The kiln may be constructed in various ways, and I have illustrated a housing which I designate generally by the numeral 7. This is of considerable length, and defines the drying chamber 70. Roof vents 71 may be supplied as is customary or desirable, and fresh air is supplied to fans, which will be described later, through a conduit 9, which extends the length of the kiln, and which may be outside of the drying chamber 70 or inside of the same, as shown herein.

Within the drying chamber a support is arranged above its bottom for a pile of lumber, illustrated at L, the pieces being piled according to any approved method to allow for circulation of air around and between the various pieces. Such a support is conveniently arranged by the transverse I-beams 12 and the longitudinal rails 73 supported thereon, on which the kiln cars C may run.

Spaced at intervals along the length of the drying chamber 70 are fans 1. These are of the type employing radial vanes 10 extending from the center of rotation outwardly, 100

and the several fans may for convenience be axially aligned and supported upon a common drive shaft 2. Each fan is encased within a casing 11, which partially encloses it; preferably about the upper three-fifths of the periphery—that is to say, somewhat more than a half of the fan, is enclosed, leaving the lower portion, say about two-fifths of the total periphery, exposed. The casing 11 fits closely about the fan, so that the air will not move round about through the casing, but this will in effect be a dead air space, holding the air within the pockets between the radial vanes 10.

Extending in a general outward and upward direction from the fan casing 11 at each side are conduits 3. Preferably these are flared outwardly from the fan, and they extend to the sides of the drying chamber 70. They are of substantially like cross-sectional area throughout, so that the effect of flaring will be merely to cause longitudinal distribution of the air passing through the fan. One of these conduits is a suction conduit and the other is a discharge conduit, or the condition may be reversed, depending upon the direction of rotation of the fan. These conduits 3, with the fan housing 11, complete a straight-through passage, with an easy angle downward from one wall of the drying chamber and upward along the opposite side wall, so that the air is led in a straight-through passage without abrupt change of direction; and without any right angle turns in the fan itself. The fan acts as a paddle wheel to keep the air moving, and the blades are spaced from the bottom 30 of the air conduit.

To heat the air and to maintain its temperature, various means may be employed. As shown herein, heating coils 13 are installed at the outer end of each of the conduits 3, steam being supplied through the main 14. Condensation is removed through the conduits 15. The presence of the heating coils 13 in the ends of the conduits 3 serves to baffle the air to some extent, and to distribute it evenly lengthwise so that the volume emitted from the extreme end of a conduit 3 is substantially the same as that emitted through the center thereof. In consequence of this, and because the conduits 3 are placed closely adjacent one another, the volume of air and its velocity is substantially the same at any given instant throughout the length of the kiln. In consequence, because of the lack of variation in volume or velocity lengthwise of the kiln, there is no tendency to endwise drift. A baffle or curtain would naturally be employed at 16, lying close to the top of the pile of lumber L, to prevent circulation over the top of the pile, and to force the air to pass through the lumber. No other baffles need be employed.

When it is desired to supply a greater volume of air, this can be done without causing an increase in the speed of rotation of the fan 1. To this end I provide a bypass conduit 4, extending from the conduit 3 at one side of a fan to the opposite conduit 3 at the other side. Between the ends of the by-pass conduit 4 communication is established with one side of the fan casing 11 through an aperture 41. At the junction with each of the conduits 3 dampers are provided, and these are designated 42 and 43 to distinguish them, though they are, or may be, of like construction and similarly controlled and operated. Each of these dampers is pivoted upon a rod 40 to control its aperture, which in the one instance is designated 44 and in the other instance 45, to distinguish them. The dampers are swung by such means as the rods 46 and 47, controlling arms 48 upon the ends of the rods 40. The rods 46 and 47 may extend the entire length of the kiln, and may control the like dampers for each of the fans, since it may be necessary because of leakage through doors and the like, at the end of the kiln, for instance, to supply a greater volume at the end than in the center, the setting of the individual arms 48, relative to the rods 46 or 47, may vary with the dampers for each fan, so that a given movement of the controlling rod, 46 or 47, will effect a different amount of movement of the several dampers.

So long as the dampers 42 and 43 are closed it is evident that no air will pass through the by-pass conduits 4 or enter at the aperture 41. I have discovered, however, that if one of these dampers is open (that one which communicates with the conduit 3 which at the moment is the suction conduit), air will be drawn through this conduit in greater volume, and a certain proportion of it, depending upon the amount of opening of the damper, will enter through the aperture 41, being drawn in by the suction created by the fan in passing this aperture, and the fan, without increase of speed, will commence to deliver a greater volume of air. With an aperture sufficiently large, the volume handled can be increased by 50%, provided the fan is properly designed. Naturally, the power required increases at such times, but the motor 20, which may be a constant speed reversible motor, would be so designed as to carry such increased load.

At times it will be desirable to supply additional fresh air, and for this purpose I have shown fresh air passages 91 connecting the fresh air conduit 9 with each of the fan casings. Such a conduit preferably is somewhat smaller than the by-pass conduit 4, and communicates with the opposite side of the fan casing through an aperture 93.

There need be no damper control for the individual fresh air passages, but all may be controlled by opening the door 92 at the entrance to the fresh air conduit 9 more or less, as may be required.

As in the case of the by-pass conduit, air will be drawn into the fan casing through the aperture 92 whenever fresh air is admitted into the fresh air conduit 9, and the suction of the fan in passing the aperture 92 will draw it in and cause it to be discharged with the circulating air into the drying chamber 70, thereby increasing the total volume discharged. As much as 20% additional volume can be supplied in this way, with the design illustrated. The amount of fresh air may be regulated, as has been indicated, by greater or lesser opening of the door or damper 93, and the maximum volume is controlled only by the size of the fan and the passage 91. The supplying of fresh air causes an increase in the load upon the fan, but as has been indicated, the motor 20 is so designed as to take care of the maximum load which might be imposed upon it.

It is believed that the operation of my kiln, and its advantages, will be apparent from the above description, and that no description in detail is necessary. It will be evident that various changes may be made in the form, proportion and arrangement of the several parts constituting the invention, without departing from the spirit thereof, as has been herein disclosed, and as will be more particularly pointed out in the following claims.

What I claim as my invention is:

1. A lumber dry kiln comprising a housing defining a drying chamber of considerable length, a plurality of fans having radiating vanes, and spaced at intervals along the length of the chamber, a fan casing partially enclosing each fan, conduits, for suction and discharge, extending from the exposed portion of each fan to each side of the drying chamber, and constituting, with the fan casing, a straight-through passage for air, reversible means to rotate the fans, a fresh air supply conduit, an individual connection from the same to each fan casing, and means to control admission of fresh air to the fan casings.

2. A lumber dry kiln comprising a housing defining a drying chamber of considerable length, a plurality of fans having radiating vanes, and spaced at intervals along the length of the chamber, a fan casing partially enclosing each fan, conduits, for suction and discharge, extending from the exposed portion of each fan to each side of the drying chamber, and constituting, with the fan casing, a straight-through passage for air, reversible means to rotate the fans, a fresh air supply conduit, an individual

connection from the same to each fan casing, and a single door controlling admission of fresh air to the fresh air supply conduit.

3. A lumber dry kiln comprising a housing defining a drying chamber of considerable length, a plurality of fans having radiating vanes, and spaced at intervals along the length of the chamber, a fan casing partially enclosing each fan, conduits, for suction and discharge, extending from the exposed portion of each fan to each side of the drying chamber, and constituting, with the fan casing, a straight-through passage for air, a by-pass conduit from the suction and discharge conduits of each fan to the fan casing, dampers controlling the passage of air through the individual by-pass conduits, a common operating means for the several dampers, and reversible means to rotate the several fans.

4. A lumber dry kiln comprising a housing defining a drying chamber of considerable length, a plurality of fans having radiating vanes, and spaced at intervals along the length of the chamber, a fan casing partially enclosing each fan, conduits, for suction and discharge, extending from the exposed portion of each fan to each side of the drying chamber, and constituting, with the fan casing, a straight-through passage for air, a by-pass conduit from the suction and discharge conduits of each fan to the fan casing, dampers controlling the passage of air through the individual by-pass conduits, a common operating means for the several dampers, means to vary the degree of opening of individual dampers relative to the others caused by said common operating means, and reversible means to rotate the several fans.

5. In a lumber dry kiln, the combination comprising a housing defining a drying chamber, a fan having its axis parallel to the length of the chamber, and having vanes radially disposed, a fan casing partially enclosing the fan, conduits, for suction and discharge, extending from the exposed portion of the fan to each side of the drying chamber, and constituting, with the fan casing, a straight-through passage for air, a by-pass conduit connecting the suction conduit with the side of the fan casing, means to control or prevent passage of air through said by-pass, and a constant speed motor for rotating the fan.

6. In a lumber dry kiln, the combination including a housing defining a drying chamber, a fan having its axis parallel to the length of the chamber, and having vanes radially disposed, a fan casing partially enclosing the fan, like conduits for suction and discharge extending from the exposed portion of the fan to each side of the drying chamber, and flared longitudinally outward.

ly of the fan, but of like capacity throughout, said conduits constituting, with the fan casing, a straight-through passage for air, a by-pass conduit extending from the suction to the discharge conduit, and communicating between its ends with the side of the fan casing, damper means to control or prevent admission of air through said by-pass to the fan casing, and reversible means to 10 rotate the fan.

7. In a lumber dry kiln, the combination comprising a housing defining a drying chamber, a fan having its axis parallel to the length of the chamber, and having vanes 15 radially disposed, a fan casing partially enclosing the fan, conduits, for suction and discharge, extending from the exposed portion of the fan to each side of the drying chamber, and constituting, with the fan casing, a straight-through passage for air, a by-pass conduit connecting the suction conduit with the side of the fan casing, means to control or prevent passage of air through 20 said by-pass, a passage to introduce fresh air to the fan casing, means to control or 25

prevent such introduction of fresh air, and means to rotate the fan.

8. In a lumber dry kiln, the combination including a housing defining a drying chamber, a fan having its axis parallel to the 70 length of the chamber, and having vanes radially disposed, a fan casing partially enclosing the fan, like conduits for suction and discharge extending from the exposed portion of the fan to each side of the drying chamber, and flared longitudinally outwardly of the fan, but of like capacity throughout, said conduits constituting, with the fan casing, a straight-through passage for air, a by-pass conduit extending from the suction to the discharge conduit, and communicating between its ends with the side of the fan casing, damper means to control or prevent admission of air through said by-pass to the fan casing, a passage to introduce 80 fresh air to the side of the fan casing opposite the by-pass, means to control or prevent such introduction of fresh air, and reversible means to rotate the fan.
